UNITED STATES PATENT OFFICE.

WEBSTER C. ESTES, OF BROOKLYN, NEW YORK.

DESIGN FOR A WOODEN BOX.

SPECIFICATION forming part of Design No. 24,203, dated April 16, 1895.

Application filed February 18, 1895. Serial No. 538,874. Term of patent 14 years.

To all whom it may concern:

Be it known that I, WEBSTER C. ESTES, a citizen of the United States, residing at Brooklyn, in the county of Kings and State of New York, have invented and produced a new and original Design for a Wooden Box, of which the following is a specification.

In the drawings, Figure 1 represents my design by an elevation. Fig. 2 is a vertical section; and Fig. 3 is a plan view of the same.

The general configuration of the box is round and the leading feature of my design consists in the central bead and the rounded top and bottom corners.

The design of the cover A of the box comprises the plain horizontal top portion a, the

plain parallel side faces b and the rounded corner c.

The design of the body portion B comprises the plain parallel side faces d that align with the side faces b of the cover, the half round bead e near the upper edge of the body, the flat bottom f and the rounded corner g.

What I claim is—

The design for a wooden box substantially as shown and described.

Signed by me this 16th day of February, A. D. 1895.

WEBSTER C. ESTES.
